UNITED STATES PATENT OFFICE.

SARA E. SLOAN, OF DENVER, COLORADO.

ONE-PIECE SLEEVE AND WAIST.

1,348,327.

Specification of Letters Patent. Patented Aug. 3, 1920.

Application filed August 9, 1919. Serial No. 316,323.

To all whom it may concern:

Be it known that I, SARA E. SLOAN, a citizen of the United States, residing at the city and county of Denver and State of Colorado, have invented certain new and useful Improvements in One-Piece Sleeves and Waists; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to garments and is especially designed for the so-called kimono waist.

The object of the invention is to provide a waist which may be cut from one piece of 20 goods and may be so put together that the seams at the side of the waist and along the sleeve will not interfere with the movements of the wearer's arms and will not be torn or stretched out of shape by such movements.

25 In the drawings:

Figure 1 is a pattern of the waist and sleeve as cut from the goods.

Fig. 2 shows the waist and sleeve partially assembled.

Fig. 3 shows the waist and sleeve in completed form.

The device comprises the front portions 10, the back 12 and the sleeves 14, the neck 35 being cut out at 16 as shown. Each sleeve has a longitudinally extending strip represented by the bracket 18, this strip being of a width equal to the length of the edge 20, which is formed by cutting into the goods 40 beyond the edge of the sleeve to the point 22. Similarly each front portion 10 has a strip represented by the bracket 24, which has a width equal to the length of the edge 120, which is formed by cutting into the 45 goods beyond the edge of the front to the point 23.

The strip 18 when the waist is put together, forms the under part of the sleeve, and the strip 24 forms the side of the waist. 50 In assembling, the corner 122 of the front 10 is brought into position at the point 22,

and the edge 28 of the back 12 is brought into contact with the edge 128 of the front 10 to form a seam 228, as in Figs. 2 and 3, the sleeve being then in the position shown 55 in Fig. 2. The corner 123 of the sleeve is then brought down under the sleeve proper to the point 23 and the edges 20 and 120 are stitched together to form a seam 220, as in Fig. 3. The sleeve edges 26 and 126 are then stitched together to form a seam 226.

In Fig. 1, the line S—S represents the top shoulder line of the waist. In Figs. 2 and 3 the lines C—C represent the center 65 side line of the garment, this line passing centrally through the armpit.

From the foregoing, it will be seen that each side of the waist is put together by means of one continuous seam, which extends up the side at the rear of the central side line C—C to the armpit, thence horizontally forward to a point forward of said line C—C, and thence to the end of the sleeve. By this construction the seam 220 75 is so located with respect to the various parts of the sleeve and waist that a very efficient hinge joint is formed which will permit the wearer to raise and lower the arms without restriction and without 80 stretching the seam and without stretching or tearing the waist.

I claim:

1. A one-piece sleeve and waist pattern, comprising, when lying flat, a sleeve portion having two longitudinal edges and one free end, a waist-back portion extending laterally of one of said longitudinal edges, and a waist-front portion extending laterally of the other of said longitudinal edges, said sleeve portion being partially severed from one of said waist portions adjacent one of said longitudinal edges on a line substantially perpendicular to said one edge, and the other of said waist portions 95 being partially severed from the sleeve portion adjacent the other longitudinal edge on a line substantially parallel with said other edge.

2. A one-piece sleeve and waist pattern, 100 comprising, when lying flat, a sleeve portion having two longitudinal edges and one

free end, a waist-back portion extending laterally of one of said longitudinal edges, and a waist-front portion extending laterally of the other of said longitudinal edges, said sleeve portion being partially severed from said waist-back portion adjacent one of said longitudinal edges on a

line substantially perpendicular to said one edge, and the waist-front portion being partially severed from the sleeve portion adjacent the other longitudinal edge on a line substantially parallel with said other edge. 10

In testimony whereof I affix my signature. SARA E. SLOAN.
